US00D470424S

(12) **United States Design Patent** (10) Patent No.: **US D470,424 S**
Hand et al. (45) Date of Patent: ** Feb. 18, 2003

(54) **SELF LEVELING ROTARY LASER**

(75) Inventors: **James C. Hand**, Glen Ellyn, IL (US);
Michael M. Zhang, Schaumburg, IL (US)

(73) Assignee: **Chicago Steel Tape Company**, Watska, IL (US)

(**) Term: **14 Years**

(21) Appl. No.: **29/157,981**

(22) Filed: **Mar. 27, 2002**

(51) **LOC (7) Cl. 10-04**

(52) **U.S. Cl. D10/69**

(58) **Field of Search** .... D10/69; 33/291, 33/295, DIG. 21; 356/138, 249, 250; 372/9-30

(57) **CLAIM**

The ornamental design for a self leveling rotary laser, as shown and described.

DESCRIPTION

FIG. 1 is a top view of a new design for a self leveling rotary laser according to our invention;

FIG. 2 is a front view thereof;

FIG. 3 is a perspective view illustrating the front and left view thereof;

FIG. 4 is a left view thereof;

FIG. 5 is another perspective view illustrating the right and rear view thereof; and,

FIG. 6 is a right view thereof.
